UNITED STATES PATENT OFFICE.

JOSEPH KENNEDY, OF NEW YORK, N. Y., ASSIGNEE TO THE CLEMENTS CO., OF NEW YORK, N. Y., A CORPORATION OF NEW YORK.

WALL-SOCKET.

1,087,299.

Specification of Letters Patent. Patented Feb. 17, 1914.

Application filed August 14, 1913. Serial No. 784,673.

To all whom it may concern:

Be it known that I, JOSEPH KENNEDY, a citizen of the United States of America, and a resident of New York, county and State of New York, have invented certain new and useful Improvements in Wall-Sockets, of which the following is a specification, reference being had to the accompanying drawings, forming a part thereof.

10 My invention relates to wall sockets or plugs, such as are inserted in walls, floors or other structures of material which will not readily receive and hold the threads of a bolt, for the purpose of forming anchorage members for the bolts or the like, and its object is to provide a simple, non-expansive shell with means which the insertion of a threaded device will cause to be securely affixed to the wall in which the shell is embedded.

I will describe my invention in the following specification, and then point out the novel features thereof in the appended claims.

25 Referring to the drawings: Figure 1 is a transverse section of a wall with a hole drilled therein with a wall socket within the hole and secured thereto by an inserted bolt. Fig. 2 is a longitudinal section partly in section, and Fig. 3 an end view of a wall socket made according to this invention. In Fig. 4 a wall socket like those shown in the preceding figures is shown in longitudinal elevation partly in section with a bolt 30 partially inserted therein. This figure illustrates the operation of the device. Figs. 5 and 6 are sectional longitudinal elevations partly in section of two modified forms of structures embodying the invention. Figs.

40 7 and 8 are end views of wall sockets made according to this invention but of still further modifications of construction. In Fig. 9 I have shown in longitudinal section another structure which also embodies the 45 present invention. Fig. 10 is a similar view of a further modification of structure made according to this invention.

Like characters of reference designate corresponding parts in all the figures.

50 According to this invention the wall socket comprises a circumferentially continuous shell of hard metal 10 through which are a plurality of holes 11. This shell is provided with a lining 12 of lead or other 55 soft material which also fills the holes 11.

When a bolt is inserted in such a device it will cut its own threads in the soft lining thereof. At the same time it will force some of the material of the lining through the holes 11 as is shown at 13 in Fig. 4.

60 The manner in which such a device is used may now be described. A hole 20 is drilled in a wall or other desired structure 21 of approximately the diameter of the shell 10 and preferably of a depth at least equal to 65 the length of the shell. The socket is then inserted in this hole and a bolt 22 or other threaded device screwed into it. This causes some of the lining material to be forced through the holes in the shell against the 70 surface of the hole and this produces a binding effect which securely affixes the socket to the structure 21 so that it will remain in place even if the bolt is removed. This is mentioned because of the fact that it is 75 sometimes desirable to detachably affix an object to the structure by means of a socket anchorage of this character.

In Fig. 5 the lining 12^A is shown tapered so that the maximum binding effect will be 80 at the inner end of the hole in which the socket is inserted. This is a preferred arrangement for it not only facilitates the insertion of a bolt but it provides for the maximum outward pressure being exerted 85 after the bolt has formed a number of threads in the lining so that any tendency it has to strip such threads is minimized. To further facilitate the insertion of a bolt the lining may be threaded a short way from 90 its outer end as shown at 14 in Fig. 5. In this figure the holes 11^A through the shell are shown as rectangular.

If desired the lining may be constructed as shown at 12^B in Fig. 6, with a plurality 95 of inwardly projecting bands progressively increasing in height toward the inner end of the device. Such a construction facilitates the insertion of a bolt and its self-thread-cutting effect. The holes 11^B through 100 the shell 10 are shown in this figure in the form of a cross.

Other ways of facilitating the insertion of a bolt and its thread cutting effect are to make the bore of the lining elliptical in 105 cross-section as at 12^C in Fig. 7, or polygonal in cross-section as at 12^D in Fig. 8. In the latter figure the outside of the shell 10^A is elliptical in cross-section. This is sometimes preferred as such a form causes the 110

socket to resist any tendency it may have to turn in the hole 20 when the bolt is being screwed in.

The wall socket illustrated in Fig. 9 comprises the perforated shell 10 of hard metal with the lining 12 of soft metal and also a cover 15 of soft metal which may be a separate sleeve or may be integral with the metal which forms the lining.

10 Fig. 10 shows the shell 10 without an internal lining, but in this case it is provided with a soft metallic cover 16 which fills the perforations in the shell and projects inwardly beyond the bore of the shell and 15 forms lugs 17 in which the bolt may cut threads.

Only such limitations are intended as are imposed in the appended claims for as I have shown herein the invention is capable 20 of being used in many forms and modifications.

What I claim is:

1. A wall socket comprising a perforated shell and a relatively soft material filling 25 the perforations and projecting inside of the bore of the shell.

2. A wall socket comprising a perforated shell of hard metal and a soft metal filling

within the perforations and projecting inside of the bore of the shell.

3. A wall socket comprising a perforated shell of hard metal and a lining of soft metal filling the perforations in said shell.

4. A wall socket comprising a circumferentially continuous perforated shell of hard 35 metal and a lining of soft metal filling the perforations in said shell and arranged to receive the threads of a bolt.

5. A wall socket comprising a hollow cylindrical perforated shell of hard metal and 40 a lining of soft metal fitting the bore of said shell and filling the perforations therein, said lining having a tapered bore.

6. A wall socket comprising a perforated shell of hard metal and a relatively soft lining therefor adapted to receive the threads of a bolt and of being forced thereby through said perforations.

In testimony whereof, I have hereunto set my hand this 7th day of August in the presence of two subscribing witnesses.

JOSEPH KENNEDY.
